Application June 25, 1946, Serial No. 679,085

8 Claims. (Cl. 171—330)

1

This invention relates generally to the generation of electrical energy and more particularly to unique methods of and means for deriving and utilizing the electrical energy of nuclear reactions.

The enormous magnitudes of energy provided by certain nuclear reactions of some radioactive substances provide a tremendous field for the development of new sources of electrical energy. Since radioactive radiations (energy) are largely electrical in nature, it is desirable that such electrical energy be converted directly to electrical energy of usable form. The alpha-particle and beta-particle emissions from certain radioactive substances comprise positively or negatively charged particle rays, respectively, having energies which vary from low values to several million electron volts. Other charged and uncharged particles also may be emitted. For example, alpha-ray emission comprises positively charged particles having energies varying from zero to the order of ten million electron volts, while beta-particle emission comprises negatively charged particles having energies varying from low values to the order of three million electron volts. Nuclear reactions are known to provide either alpha-particle emission, beta-particle emission, or a combination of alpha-particle and beta-particle-emission, as well as other types of charged and uncharged particles not generally so well known. The direct utilization of the high electrical potentials which may be derived from such charged particles provides, in the cases in which the particle emission is charged, much more convenient and efficient utilization of nuclear energy than previously proposed systems wherein the nuclear energy is converted to thermal energy, the thermal converted to mechanical energy, and the mechanical energy then converted to electrical energy in a usable form. Also, the direct utilization of the electrical energy of nuclear reactions may be much more readily controlled by electrical methods than may the conversion of nuclear energy to thermal energy.

The instant invention is an improvement over the methods and systems described and claimed in applicant's copending U. S. application, Serial No. 679,081, filed June 25, 1946, now Patent No. 2,517,120, August 1, 1950, which contemplates the use of collector electrodes for collecting the charged particle rays from a radioactive source, and means for applying the resultant unidirectional potential between the source and collector electrodes to a load. The improvement comprising the instant invention includes unique

2

methods of and means for segregating and utilizing separately the electrical properties of alpha-particle and beta-particle or other charged particle emission from radioactive materials to generate separate voltages and thence combining said voltages. It utilizes the distinguishing characteristics of differences in charge, polarity, mass, velocity and penetration of different types of such particles.

10 Among the objects of the invention are to provide improved methods of and means for generating electrical energy in response to nuclear reactions. Another object is to provide improved methods of and means for utilizing the electrical energy in nuclear reactions for generating high unidirectional potentials. A further object is to provide improved methods of and means for utilizing the electrical energy of nuclear reactions for generating alternating potentials. An additional object is to provide improved methods of and means for utilizing atomic energy for generating electrical energy. A still further object of the invention is to provide improved methods of and means for utilizing radioactive materials 15 as sources of electrical energy.

20 Another object of the invention is to provide improved methods of and means for converting atomic energy directly to electrical energy in commercially usable forms. A still further object is to provide improved methods of and means for segregating and separately utilizing the electrical energy of alpha-ray and beta-ray or other charged particle emissions of radioactive materials 25 for generating electrical energy.

30 Other objects of the invention include improved methods of and means for converting the electrical energy of nuclear reactions of radioactive materials to high frequency electrical energy. A still further object is to provide improved methods of and means for utilizing and combining the alpha-ray and beta-ray electrical potentials of 35 nuclear reactions for directly deriving electrical energy in commercially usable form.

40 The various embodiments and features of the invention will be described in detail hereinafter by reference to the accompanying drawings of which Figure 1 is a schematic diagram of a basic embodiment of the invention according to said copending application and including a simple unidirectional voltage generator; Figure 2 is a 45 cross-sectional diagram of a modification of said basic embodiment of the invention; Figure 3 is a cross-sectional schematic diagram of another modification of said basic embodiment of the invention; and Figures 4 and 5 are cross-sectional,

partially-schematic diagrams of first and second embodiments of the instant invention each utilizing combinations of alpha-ray and beta-ray emission for generating electrical energy. Similar reference characters are applied to similar elements throughout the drawings.

High-voltage D.-C. generators

Referring to the drawings, Figure 1 illustrates the simplest form of the basic embodiment of the invention disclosed and claimed in said co-pending application comprising a unidirectional high voltage generator 1. The generator 1 includes a source 3 of alpha-rays or beta-rays derived from a quantity of radioactive material. A 15 suitable alpha-ray radioactive source may comprise, for example, a quantity of polonium (84Po²¹⁰). Likewise, a suitable beta-ray source may comprise a suitable quantity of radioactive phosphorus (15P³²). Radioactive phosphorus is a pure beta-ray emitter which becomes stable after emission. It is thus suitable for use as an electronic power source since it emits no gaseous reaction products and, therefore, it is suitable for vacuum applications. One gram of this material occupies about .5 cubic centimeter and will emit about 2 milliamperes of electron current. The maximum energy of the beta rays is of the order of 1.7 million electron volts, but only a small fraction of the electron current would be available at such a high voltage. However, about 1 milliampere of current would be emitted at one megavolt. Since the average energy of emission would be about 1 million electron volts, the total electrical energy or power emitted would be about 2 kilowatts. The half-life period of radioactive phosphorus (15P³²) is about 14 days, and the current and power would decrease exponentially to one-half their initial values in that time.

The radioactive source 3 is surrounded, for example, by a spherical highly evacuated conductive collector electrode 5 having an aperture insulator 7 therein for a suitably insulated terminal 9 for the radioactive source 3. A load 11 is connected between the collector electrode 5 and the source terminal 9. If desired, the collector electrode 5 may be grounded.

In operation, and in the absence of a load, beta particles (electrons) emitted by the radioactive source 3 travel to the collector electrode 5 and charge it negatively as indicated by the dash line arrow 13. The charge upon the collector electrode is negative with respect to the source 3 and increases until the potential of the collector electrode is sufficiently high to repel additional electrons arriving from the source 3 is shown by the dash line arrow 15. If it is assumed that the radioactive source 3 emits 1 megavolt electrons (beta rays), the potential of the collector electrode 5 would reach one megavolt and would be negative with respect to the radioactive source. If a load is connected between the collector electrode and the source terminal, a current will flow through the load and power will be dissipated therein. Thus the radioactive energy emitted in the beta rays may be employed directly in its original electrical form to provide electrical energy.

Known beta-ray emitters provide electrons having energies from almost zero to 3 million electron volts. Known alpha-ray emitters provide positively charged alpha particles having energies from about zero to the order of 10 million electron volts. If desired an alpha-particle source may be employed instead of a beta par-

ticle source, in which case the collector electrode 5 will be charged positively until it reaches a potential sufficiently high to repel additional alpha particles. In such a modification of the invention, the collector electrode 5 becomes the positive terminal and the radioactive source 3 the negative terminal of the generator. Obviously other types of charged particles may be utilized.

The electric current produced by any source of charged particles is

$$i = e = \frac{dn}{dt} \quad (1)$$

where n is the number of particles emitted, t is the time in seconds, and therefore dn/dt is the rate of particle emission, and e is the electrical charge per particle. If each particle carries more than one electronic charge, e must be replaced by μe , where μ is the number of charges.

For a radioactive substance

$$dn/dt = -\lambda n \quad (2)$$

(see Pollard and Davidson, Applied Nuclear Physics, p. 105), where λ is the decay constant and is related to the half life t_H by the equation

$$\lambda = \frac{0.693}{t_H} \quad (3)$$

From Equations 1, 2 and 3 it is seen that

$$i = -\mu e n \frac{0.693}{t_H} \quad (4)$$

The number of atoms contained in a substance of mass M and atomic weight A is

$$n = \frac{M}{m_H A} \quad (5)$$

where m_H is the mass of the hydrogen atom. Thus

$$i = -\frac{0.693 M \mu}{m_H A t_H} \quad (6)$$

This relation may be expressed in amperes per gram for a predetermined quantity of a radioactive substance wherein $e=1.59 \times 10^{-19}$ coulombs, $M=1$ gram, $m_H=1.66 \times 10^{-24}$ grams, and $t_H=8.64 \times 10^4 T_H$, where T_H is the half life in days. Therefore,

$$i_1 = \frac{0.76 \mu}{A T_H} \quad (7)$$

If the radioactive source is polonium, $A=210$ and $T_H=140$, $\mu=2$, therefore

$$i_1 = \frac{0.76 \times 2}{210 \times 140} = 51.8 \times 10^{-6} \text{ amps./gram} \quad (8)$$

$$= 51.8 \text{ microamps./gram}$$

The characteristics of the charged particle emitting substance determine not only the output voltage of the generator, but also determine its impedance. Thus, since alpha particles generally have a very uniform energy, the generated voltage would remain substantially constant until all the remaining current was drawn, whereupon the voltage would decrease rapidly. Thus, with an alpha-particle emitter, the generator would have a low effective internal impedance. In contradistinction thereto, beta particles are usually emitted over a wide energy range which may vary from a very low value to several million electron volts.

Consequently, when current is drawn from the generator to a load, the load voltage would immediately drop to a much lower value than the no load maximum, as is characteristic of all generators having high internal impedance. The actual variation of load voltage with current

would depend upon the particular characteristics of the beta-ray emitting material. In general the available power depends upon the quantity of radioactive material employed and upon its rate of particle emission. Materials which emit at high rates have short operating life, while materials emitting at low rates have relatively longer operating lives. A D.-C. generator of the type described has particular application for systems requiring high voltage and low power capacity since in such instances only a relatively small amount of radioactive material is required for the alpha- or beta-ray source.

For generators providing relatively large power values, cooling of the charged particle source may be necessary or desirable since the source is bombarded and heated by the returning charged particles which are reflected by the charged collector electrode. Also the collector electrode is heated by the charged particles which it collects. A simple system for cooling the charged particle emitter is shown in said copending application wherein the charged particle source 3 comprises a relatively thin shell of radioactive material into which air or water under pressure may be forced for cooling purposes. If desired, the collector electrode 5 may be cooled by air blasts.

Secondary electron suppression

The principal limitations on the potentials which may be attained by the device described heretofore is due to leakage currents. Some of the leakage currents are due to the inherent limitations of insulating materials and the proportions thereof as determined by the proportions of the generator unit. Insulator leakage currents may be reduced to negligible values by employing insulator materials and shapes commonly used in high voltage work. Another serious source of leakage currents arises from the nature of radioactive radiations themselves.

Referring again to Figure 1 of the drawings, beta rays striking the collector electrode 5 will cause secondary electron emission therefrom. Such secondary electrons will be attracted toward the radioactive source 3 which is positively charged with respect to the collector electrode 5, and thus will tend to neutralize the positive charge on the radioactive source and hence decrease the potential difference between the source 3 and the collector 5.

Referring to Figure 2, in order to reduce the effect of secondary electron emission from the collector electrode 5, a grid or thin metallic shell 17 is introduced into the generator in a region intermediate the source 3 and collector 5, and is maintained at a comparatively small negative potential with respect to the collector electrode 5 by a battery 19 connected between the collector and grid electrodes. The biasing potential may be of the order of 100 to 1000 volts. As explained heretofore, this potential may be derived from a separate radioactive D.-C. generator since the energy required is practically negligible. The negatively biasing grid electrode 17 suppresses substantially all secondary electrons emitted by the collector electrode 5 and thus permits the potentials between the radioactive source 3 and the collector electrode 5 to build up to a value determined by the velocity of emission of the beta rays and the load resistance, as described heretofore.

Alpha-particle suppression

A further source of leakage would occur in instances wherein the radioactive source 3 emits

positively charged alpha particles as well as negatively charged beta particles. The alpha particles in traveling to the collector electrode 5 would neutralize some of its negative charge and thus reduce the potential existing between the radioactive source and the collector electrode. In such instances the radioactive source 3 may be enclosed within a thin metallic envelope 21. The envelope 21 should be of such material and thickness (for example, aluminum of .005") that it is substantially opaque to alpha-particle emission but is substantially transparent to beta-particle emission.

Delta-particle suppression

Referring to Figure 3, when an alpha-particle radioactive source is employed, leakage may result due to δ rays which are slow electrons which accompany the emission of alpha rays. Such δ rays would be drawn to the collector electrode 5, which in this instance would be positively charged with respect to the alpha emitting source 3, and would result in charge neutralization on the collector electrode. To decrease this effect, the alpha particle emitting source 3 may be surrounded by a grid 23 which is maintained at a comparatively low negative voltage with respect to the alpha-particle source 3. This voltage may be derived from an external battery 25 connected between the source 3 and the grid 23 or it may be derived from an auxiliary radioactive generator. The bias voltage applied to the grid 23 should be sufficiently high to suppress and reflect back to the source substantially all δ rays emitted by the radioactive source 3, but will have little effect upon the highly positively charged alpha particles emitted by the source.

Controllable radioactive generators

When employing radioactive materials (either natural or artificial) for the production of electrical energy, the radioactive emission will decay exponentially as a function of the type of radioactive material employed. The decay of radioactive emission will provide a corresponding decrease in the energy which may be derived from the generator. This decay is uncontrollable since the active material is consumed whether or not power is derived from the generator.

By utilizing a reaction or series of reactions of the proper types, it is possible to provide a radioactive electric generator which will consume the radioactive material and deliver electrical energy only when desired. An example of such a reaction is as follows:

This series of reactions is initiated by bombarding uranium 238 with neutrons and results in the production of two beta particles per molecule of U^{238} . A suitable source of neutrons would be uranium 235.

An example of a generator using a controllable radioactive source is disclosed and claimed in applicant's copending U. S. application, Serial No. 679,084, filed June 25, 1946. It should be understood that the neutron and radioactive chain reactions may be initiated and controlled in any other manner and with any other structure known in the art.

Following is a partial list of alpha- and beta-

ray emitters which are suitable for high voltage generators of the types described heretofore:

Element	Half-life, days	Energy, equivalent million electron volts
ALPHA-RAY EMITTERS		
Polonium (Po ²¹⁰)	140	5.25
Actinium (Ac ²²³)	11.2	5.66
Thorium X (Th X ²²⁴)	3.64	5.65
Radio actinium (Rd Ac ²²⁷)	18.9	5.92
BETA-RAY EMITTERS		
Phosphorus (P ³²)	14	1.7
Calcium (Ca ⁴⁶)	180	0.2
Scandium (Sc ⁴⁶)	85	0.26
Iron (Fe ⁵⁹)	47	0.4
Arsenic (As ⁷⁵)	16	1.3
Srontium (Sr ⁸⁹)	55	1.5
Antimony (Sb ¹²¹)	60	1.53
Tungsten (W ¹⁸⁵)	77	0.5

Combined alpha- and beta-ray generators

High voltage D.-C. generators may be provided to utilize a radioactive emitter providing both positive and negative charged particles (alpha and beta rays or other charged particles of both polarities and differing velocities and penetration). An emitter of both alpha and beta particles is radium (C). A mixture of substances such as radioactive polonium and radioactive phosphorus also may be utilized. The polonium provides pure alpha ray emission, and the radioactive phosphorus provides pure beta-ray emission. Such mixtures are frequently preferable since the ratio of the number of alpha and beta particles may be controlled.

Referring to Figure 4, a radioactive source 21 providing both alpha and beta particle emission is supported by terminal 29 from a high voltage insulator 31 which also supports a spherical evacuated beta-ray collector electrode 33. A thin metallic alpha-ray collector electrode 35 is interposed between the source 21 and the beta-ray collector electrode 33. The alpha-ray collector electrode should be of sufficiently thin material to be substantially opaque to alpha rays while substantially transparent to beta rays, as explained heretofore by reference to the device illustrated in Figure 2. A terminal 31 supports the alpha-ray collector electrode 35 and is insulated by a second high voltage insulator 39 from the beta-ray collector electrode 33.

In operation the alpha-ray collector electrode 35 becomes positively charged to the potential of the alpha rays, and the beta-ray collector electrode 33 becomes negatively charged to the potential of the beta rays, both with respect to the source 21. The voltage which may be applied to a load 41 thus is the sum of the magnitudes of the voltages established on the electrodes 33 and 35.

It is essential for proper operation of the device that the rate of arrival of alpha particles on the alpha-ray collector electrode 35 exceed the rate of arrival of beta particles by direct capture and by reflection from the beta-ray collector electrode 33. Suitable proportions of alpha-ray and beta-ray radiation may be assured by providing a suitable mixture of alpha-ray and beta-ray emissive substances in the radioactive source 21.

A more complex structure utilizing combined

alpha-ray and beta-ray emission for generating high D.-C. voltages is shown in Figure 5 wherein a combined alpha ray and beta ray emissive source 43 is in the form of a hollow shell which is insulated from and surrounded by an evacuated spherical beta-ray collector electrode 45. A secondary electron suppressor grid or thin shell 47 is interposed between the beta-ray collector electrode 45 and the radioactive source 43 to prevent secondary electron emission from the beta-ray collector electrode from reaching and neutralizing the potential of the radioactive source 43. An alpha ray suppressor electrode 49 comprising a thin sheet of aluminum or other suitable material opaque to alpha-ray emission but substantially transparent to beta-ray emission surrounds the external surface of the radioactive source 43. Thus the voltage on the beta-ray collector electrode 45 with respect to the radioactive source 43 is substantially dependent only upon beta-ray emission.

An alpha-ray collector electrode 51 is disposed at the center of the hollow radioactive emitter 43 and is insulated therefrom in any suitable manner. A beta-ray suppressor grid 53, biased negatively with respect to the radioactive source 43, is disposed between the alpha-ray collector electrode 51 and the radioactive source 43. The negative potential for the beta-ray suppressor grid may be derived by means of a direct connection between said grid and the beta-ray collector electrode 45 whereby said grid is self-biased by the beta-ray emission.

The voltage established upon the alpha-ray collector electrode 51 thus is dependent substantially only upon the alpha-ray emission from the radioactive source 43. The sum of the voltages developed upon the beta-ray collector electrode 45 and the alpha-ray collector electrode 51 may be applied directly to a load 55.

One of the advantages of the more complex structure illustrated in Figure 5 over the simple combination alpha and beta ray generator of Figure 4 is that undesirable reaction upon the alpha ray collector electrode due to reflected or secondarily emitted electrons from the beta-ray collector electrode is substantially eliminated, thus reducing leakage currents. It should be understood that the relative positions of the alpha-ray generator portion and the beta-ray generator portion of the device may be interchanged with respect to the radioactive source. The principles and techniques of the instant invention also may be applied to the generation of alternating potentials including energy of microwave frequency by proportioning the collector electrodes to resonate at the desired output frequency as disclosed and claimed in applicant's copending U. S. application, Serial No. 679,083, filed June 25, 1946.

Thus the invention described and claimed herein comprises unique methods of and means for generating unidirectional or alternating potentials by utilizing directly the electrical properties of radioactive emission. Such generators may provide high or low unidirectional potentials with relatively low or relatively high current output, respectively; and alternating potentials including A.-C. energy of microwave frequency. Control and focusing potentials for said devices may be provided by auxiliary radioactive generators, or self-biasing arrangements may be employed. Combinations of both alpha- or beta-ray emission may be segregated or utilized separately.

I claim as my invention:

1. The method of utilizing a source of radioactive material providing positively-charged-particle and negatively-charged-particle emission for generating electrical energy comprising segregating and collecting said positively-charged-particle emission in a first region adjacent to said source to establish a first potential with respect to said source, collecting said negatively-charged-particle emission in a second region adjacent to said source to establish a second potential with respect to said source, substantially preventing charged particle interaction between said regions, and combining said potentials.

2. Apparatus for generating electrical energy including a source of radioactive material providing both alpha-particle and beta-particle emission, means disposed adjacently to and in operative relation with said source for collecting said alpha-particle emission to establish a positive potential with respect to said source, second means disposed adjacently to and in operative relation with said source for collecting said beta-particle emission to establish a negative potential with respect to said source, means for substantially preventing alpha-particle irradiation of said second means, and means for combining said potentials.

3. Apparatus for generating electrical energy including a source of radioactive material providing both alpha-particle and beta-particle emission, first means substantially transparent to beta-particle emission and substantially opaque to alpha-particle emission surrounding said source for collecting said alpha-particle emission to establish a positive potential with respect to said source, second means surrounding said source and said first means for collecting said beta-particle emission transmitted through said first means to establish a negative potential with respect to said source, and means for combining said potentials.

4. Apparatus for generating electrical energy including a source of radioactive material providing both alpha-particle and beta-particle emission, first means substantially transparent to beta-particle emission and substantially opaque to alpha-particle emission surrounding said source, second means surrounding said source for collecting said beta-particle emission transmitted through said first means to establish a negative potential with respect to said source, third means in operative relation with said source for collecting substantially only said alpha-particle emission to establish a positive potential with respect to said source, and means for combining said potentials.

5. Apparatus for generating electrical energy including a hollow body source of radioactive material providing both alpha-particle and beta-particle emission, first screen electrode means substantially transparent to beta-particle emission and substantially opaque to alpha-particle emission surrounding said source, second means surrounding said source and said first means for collecting said beta-particle emission to establish a negative potential with respect to said source, a secondary-electron-suppressor electrode disposed between said first and second means for

preventing secondary-electron emission from said second means from reaching said source, third means disposed within said hollow source for collecting substantially only alpha-particle emission to establish a positive potential with respect to said source, a beta-particle suppressor electrode disposed between said third means and said source for substantially preventing beta-particles from reaching said third means, and connections to said second and third means for combining said potentials.

6. The method of utilizing a source of radioactive material providing positively-charged-particle and negatively-charged-particle emission for generating electrical energy comprising segregating said charged particles as a function of their penetrating characteristics in a retarding medium, collecting said positively-charged-particle emission in a first region adjacent to said source to establish a first potential with respect to said source, collecting said negatively-charged-particle emission in a second region adjacent to said source to establish a second potential with respect to said source, and combining said potentials.

7. The method of utilizing a source of radioactive material providing positively-charged-particle and negatively-charged-particle emission for generating electrical energy comprising segregating said positively-charged-particles as a function of their penetrating characteristics in a retarding medium, collecting said positively-charged-particle emission in a first region adjacent to said source to establish a first potential with respect to said source, segregating said negatively-charged-particles as a function of their penetrating characteristics in said retarding medium, collecting said negatively-charged-particle emission in a second region adjacent to said source to establish a second potential with respect to said source, and combining said potentials.

8. The method of utilizing a source of radioactive material providing positively-charged-particle and negatively-charged-particle emission for generating electrical energy comprising segregating said charged particles as a function of their penetrating characteristics in a retarding medium, collecting said positively-charged-particle emission in a first region adjacent to said source to establish a first potential with respect to said source, collecting said negatively-charged-particle emission in a second region adjacent to said source to establish a second potential with respect to said source, and utilizing said potentials.
